UNITED STATES PATENT OFFICE

2,623,486

DARNING MACHINE FOR HOSE-SHAPED WORK

Karl Scheiwiller, Saint Gallen, Switzerland, assignor to Brutsch & Co., Zurich, Switzerland, a Swiss corporation

Application August 4, 1948, Serial No. 42,433
In Switzerland June 1, 1948

2 Claims. (Cl. 112—121)

1

With the known sewing, darning or mending machines with a free working arm the uniform tensioning and displacing of the hose-shaped work, such as stockings or socks, with the help of the shape of the work arm of the machine is connected with difficulties. Also the lifting of dropped meshes by means of dropped-mesh lifters is tedious and only to be done with difficulty since the hose-shaped work can only be tensioned with one hand.

The object of the present invention is a darning machine adapted in particular for hose-shaped work, such as stockings and the like, having an upper arm and connected with it by means of an intermediate part a lower arm with a broadened head, a driving shaft rotatably mounted and transmission means for the drive of a needle-rod arranged in the upper arm, and a shaft with the spool rotatably arranged in the lower arm, the drive and spool shaft being compulsorily connected with each other and geared to each other in such a manner that the spool shaft rotates twice as fast as the shaft in the upper arm.

The object of the present invention is illustrated by way of two examples in the enclosed drawings in which:

Fig. 1 is a section through the darning machine according to the first embodiment,

Fig. 2 a view in perspective according to Fig. 1,

Fig. 3 gives a section through a darning machine according to another embodiment.

The darning machine according to the first embodiment shown in Figures 1 and 2 has a stand with an upper arm 1, a lower arm 2 and an intermediate part 3 which connects the two arms with each other and secures them in the correct position to each other. In the upper arm a drive shaft 4 is mounted rotatably in the bearings 5 and 6. At its left hand end it is provided with a crank 7, the crank pin 8 of which is connected to pivot 10 of needle rod 11 by means of connecting rod 9, and on rotation of the driving shaft 4 the crank moves the needle rod having the needle 12 secured to its lower end up and down. The needle rod is displaceably and vertically guided in bearings 13 and 14 in upper arm 1, and on its lower part two dogs 15 and 16 are secured with which it operates the lever 17 of a dropped mesh device when the needle rod is moved up and down by the driving mechanism. On the driving shaft 4 the eccentric 19 for the operation of the thread tensioner 20 and in addition the bevel gears 21 and 22 are secured. The bevel gear 21 meshes with the small bevel gear 55

2

23 arranged below it and secured to the vertical shaft 24, said shaft being mounted in the bearings 24-a and 24-b and having rigidly connected to its lower end the bevel gear 25. This bevel gear meshes with the bevel gear 26 which is securely fixed to shaft 27 rotatably mounted in bearings 27-a and 27-b setting said shaft in rotation. The end of shaft 27 pointing upward is stepped back in bearing 27-b and on its head 28 with the circular shuttle is pushed on so that said shuttle together with the head can be easily exchanged. The circular shuttle 28 is covered by means of a semi-spherical cap 31 which is supported by arm 2. The cap itself is provided with an opening 32 through which needle 12 can cooperate with the shuttle. Above the cap the dropped-mesh lifter 33 is arranged on the lower side of upper arm 1 on bearing 18 for pivoting about bearing pin 34. The needle 35 of said lifter is moved to and fro by the lever 17 pivoting about pin 36 on bearing 18 by means of the dogs 15, 16 on the needle rod when the latter is reciprocated. The other bevel gear secured to drive shaft 4 serves for driving the driving shaft. 25 With it the bevel gear 37 fixed to the rotor shaft of the electric motor 38 meshes. The electric motor 38 itself is carried for oscillation about axis 39 by bearing stirrup 40 fixed to the intermediate part 3. At the upper end of said motor a tension spring 41 is provided one end of which is fixed to the inside of upper arm 1 and the other end to the motor in such a manner that the bevel gear 37 is elastically held in mesh with gear 22. The current supply is led in by means of plug 42 and cable 43, the current interruption being capable of being carried out by means of a known cut-out switch operated by the feet or the knee. In addition a bevel pinion 45 secured to shaft 44 arranged at right angles to driving shaft 4 meshes with the bevel gear 22, shaft 44 having a small hand wheel 48 arranged on the outside of the upper arm, said wheel enabling the needle rod to be moved by hand. In the bottom of upper arm 1 a small lamp 46 for illumination of the place of work is adjustably fitted. A clamping device 47 on the intermediate part serves for fixing the machine to a table or the like.

The darning machine according to another embodiment is represented in section by Figure 3. The upper arm 84 and the lower arm 85 are arranged parallel to each other, but inclined at an angle of 45° to the horizontal. For driving the needle rod 73 and the needle 66 a crank disk 69, a crank 70 and a connecting rod 71 are again used, said connecting rod connecting with the

head 72 of the needle rod 73. The crank disk 69 is securely fixed to the right hand end of the driving shaft 49, on which shaft the chain wheel 86 is mounted and on the left hand end the hand wheel 87 are secured. In the lower arm 85 the gripper shaft 88 is rotatably mounted, said shaft carrying the gripper 89 securely at its right hand end. On the left hand side of gripper shaft 88 the chain wheel 89 is securely connected with it. The chain wheels have a ratio of two for chain 10 wheel 86 and one for chain wheel 89 and over the two a common endless chain 90 is slung. On the outer end of the left hand side of shaft 88 a friction wheel 91 is secured which is in contact with the small friction wheel 92 of the electric motor 93 said motor being mounted in the housing 95 of the sewing machine for oscillation about axis 94. A tension spring 96 holds the small friction wheel 92 on the motor shaft in contact with the large friction wheel 91. In connection with a switch not shown in the drawing the sewing machine can be put into or out of operation in any desired manner by the electric motor 93.

Instead of the transmission of motion between the driving and the gripper shaft by means of a chain a connecting shaft with a pair of bevel gears each at each end of the shaft can be used. All the known additional equipment in particular, such as for zigzag darning or darning with a ring, can be used with the machine.

The machine is normally fixed to the table at right angles to the table edge.

However, a stud with a ball-head can be provided on the machine base, which ball-head can be clamped in a ball-socket in its turn clamped to the table thus enabling the machine to be tilted and secured in any position desired.

What I claim is:

1. A darning machine, for hose-shaped work such as stockings, including an upper arm, a crankshaft rotatable in said upper arm, a displaceable needle bar with a needle positioned at right angles to said crankshaft, a head for supporting the work piece arranged opposite to said needle and connected with said upper arm, said head being broadened on its top and formed with an arched surface, a circular shuttle rotatably arranged in said head in operative connection with said needle for forming loops, a drive shaft

on which said shuttle rotates in positive connection with said crankshaft and forming loops with said needle, said crankshaft, needle bar, and needle being positioned at an obtuse angle to said drive shaft of said shuttle and said darning head, a downward receding arm positioned at an obtuse angle to the horizontal, on the end of which said circular shuttle is arranged.

2. A darning machine for hose-shaped work such as stockings, including an upper arm, a crankshaft rotatable in said upper arm, a displaceable needle bar with a needle positioned at right angles to said crankshaft, a head for supporting the work piece arranged opposite to said needle and connected with said upper arm, said head being broadened on its top and formed with an arched surface, a circular shuttle rotatably arranged in said head in operative connection with said needle for forming loops, a driveshaft on which said shuttle rotates in positive connection with said crankshaft and forming loops with said needle, said crankshaft, needle bar, and needle being positioned at an obtuse angle to said drive shaft of said shuttle and said darning head, a downward receding arm positioned at an obtuse angle to the horizontal, on the end of which said circular shuttle is arranged, the crankshaft being positioned horizontally and having a vertically arranged axle driving the axle of the circular shuttle at an obtuse angle.
